FORCED DRAFT UNIT FOR OIL BURNERS

James L. Breese and Bruce Hayter, Santa Fe,
N. Mex., assignors to Oil Devices, Santa Fe,
N. Mex., a limited partnership of Illinois

Application October 21, 1939, Serial No. 300,593

7 Claims. (Cl. 158—91)

Our invention relates to an improvement in oil burners and has for one purpose to provide a simple and inexpensive forced draft unit in which means for forcing a circulation of air are associated with a burner. Our invention is herein shown as applied to a pot type burner.

Another purpose is the provision of means for cooling or preventing the heating of a fan motor, while maintaining it in operating proximity to an oil burner.

Another purpose is the provision of improved mounting means for fan and motor.

Other purposes will appear from time to time in the course of the specification and claims.

We illustrate our invention more or less diagrammatically in the accompanying drawings wherein:

Fig. 1 is a side elevation with parts in section; Fig. 2 is a vertical section on an enlarged scale;

Fig. 3 is a section on the line 3—3 of Fig. 1 on an enlarged scale; and

Fig. 4 is a section on the line 4—4 of Fig. 1 on an enlarged scale.

Like parts are indicated by like symbols throughout the specification and drawings.

Referring to the drawings, 1 indicates an outer drum or housing provided with bottom air inlet apertures 2. 3 indicates an angle ring extending around the interior of the drum 1 and adapted to receive a supporting flange 4 of the inner drum 5. Positioned within the inner drum is the pot 6, herein shown as provided with a plurality of air inlet apertures 7 arranged in a plurality of horizontal rows. Any suitable means may be employed for supplying secondary air, but we illustrate a top row 8 of secondary air inlet apertures, which are shown as larger and more closely spaced than the apertures 7.

The pot 6 is illustrated as having a top flange 9 with a circumferential downward edge 10 seating upon and conforming closely to the upper edge of the drum 5 and forming a substantially air tight closure therewith.

The drum 5 has any suitable bottom member 11, provided with a central axial aperture 12. Herein shown as secured to the bottom member 11 is a bottom disc 13 having an upwardly extending circumferential flange 14 and a further outward extension or ring 15, which conforms to and may be secured to the bottom 11, as by a plurality of headed studs 16 extending downwardly from the bottom 11 and seating in slots 17 in the ring or flange 15. Each of these slots terminates in an enlarged aperture 18, whereby, upon slight rotation of the plate 13, the plate

and all parts mounted thereupon may be bodily removed from the bottom 11.

The flange 14 is provided with a plurality of air inlet apertures 20 whereby air may enter from the interior of the drum 1 to the space defined by the members 11, 13 and 14, and thence through the central aperture 12 to the space between the inner drum 5 and the pot 6, for entry through the primary and secondary air inlet apertures 7 and 8.

Supported below and upon the disc 13 we provide a motor housing including a top plate 25 and a housing box 26 secured thereto, as by rivets 27 or by any other suitable securing means. 15 Mounted within the box 26 is a motor 28, the details of which do not of themselves form part of the present invention. A motor shaft 29 extends upwardly through an offset 30 of the plate 25, which is aligned with and extends upwardly into the aperture 31 in the disc 13. Mounted upon the motor shaft 29 is any suitable hub 32, carrying a fan body 33 having generally flat radial plates 34 having upwardly extending flanges or fan vanes 35. This fan structure extends upwardly into and conforms generally to the aperture 12, with the vanes 35 extending above the level of the bottom 11.

If desired, we may employ fixed air distributor members 36, outwardly extending from the upper surface of the bottom plate 11. We may employ any suitable means for supporting the motor housing, but we illustrate for example blocks of yielding compressible material 37 of rubber or the like, through which may pass securing screws 38, the lower ends of which penetrate outer portions of the plate 25. 39 is any suitable lubricating inlet for the box 26, which may be closed for example by the cap 40, available for easy lubrication.

40 41 is a fuel line extending to the bottom of the pot 6. Any suitable valve means 42 may be employed for controlling the volume of flow of the liquid fuel. 43 is any suitable conduit adapted to carry conductors 44, which pass integrally through an elbow 45 for connection to the motor 28. It will be observed that the fuel line 41 and the conduit 43 pass inwardly through the drum 1 through appropriate apertures.

50 It will be realized that whereas we have described and illustrated a practical and operative device, nevertheless many changes may be made in the size, shape, number and disposition of parts without departing from the spirit of our invention. We therefore wish our description and drawings to be taken as in a broad sense

illustrative or diagrammatic, rather than as limiting us to our precise showing.

The use and operation of our invention are as follows:

Under some circumstances we find it advantageous to provide a simple and inexpensive forced draft unit, herein shown as applied to a pot type burner. Such forced draft means are advantageous, for example, for ranges and for hot water heaters. We therefore provide a small motor 28, completely housed in the member 26 and preferably running submerged in oil. It drives the small paddle wheel fan carrying the vanes 35. The housing 26 is attached to the air intake plate 13, for example by means of the resilient rubber mountings 37. The intake unit is bodily removable, by mere rotation, and may be removed with fan and motor. To fasten the unit as a whole to the burner, it is simply placed with the apertures 18 passing over the heads of the studs or rivets 16 and given a slight twist.

To avoid any possibility of the unit coming loose, we may employ a screw 50 passing through a clip 51, which in turn may be secured to the ring 15.

Air distributors or fixed vanes 36 are effective to remove the swirl of the air occasioned by the employment of the fan without a surrounding housing. It is important that the air enter radially rather than tangentially in order not to destroy the balance of combustion, and the vanes 36 as shown have this effect. The flow of air inwardly through the apertures 20 and up through the fan serves as a cooling or protective medium interposed between the motor and the burner. The air which moves rapidly inwardly through the apertures 20, upwardly through the fan, and outwardly across the bottom of the pot 6, prevents any tendency of the motor to heat. Since the motor runs in a permanent bath of oil, it will operate with a minimum of attention or inspection. The rubber mounting removes all traces of vibration.

A very small motor can be employed, and the power consumption of the unit is so low that it may, if desired, be continuously operated.

The present invention is particularly advantageous in that it enables the utilization of the burner housing as a blower housing, without the employment of any separate or additional blower housing.

We claim:

1. In combination, a burner pot having air apertures at a plurality of levels in the side wall thereof, means for delivering a liquid fuel to the interior of the pot, and means for delivering air under pressure to the space about the exterior of said pot, including an air tight housing surrounding said pot and having a bottom with an air inlet aperture vertically aligned with the center of the pot bottom, and a forced draft unit including a plate, a motor on said plate, a motor shaft mounted for rotation about a generally vertical axis and a fan mounted on said motor shaft, means for supporting said plate below and spaced downwardly from the bottom of said housing, with the axis of said fan aligned with the center of the aperture in said bottom and with the central axis of the pot, said fan comprising vanes extending upwardly from the plane of said housing bottom and located radially substantially within the periphery of said pot, air being free to flow into the space between said plate and the bottom of the housing, and means located between the pot bottom and the bottom

of the housing and in the space defined therebetween for causing a radial delivery of the air delivered by said vanes, including a plurality of fixed vanes mounted on and upwardly extending from the bottom of the housing, and located in the direct line of delivery of air from the fan vanes, and terminating at their outer edges adjacent the periphery of the pot, said fixed vanes including generally radial inner portions and being curved laterally toward their outer delivery edges, whereby a substantially circumferential movement is imparted to the air delivered thereby.

2. In combination, a burner pot having air apertures at a plurality of levels in the side wall thereof, means for delivering a liquid fuel to the interior of the pot, and means for delivering air under pressure to the space about the exterior of said pot, including an air tight housing surrounding said pot and having a bottom with an air inlet aperture vertically aligned with the center of the pot bottom, and a forced draft unit including a motor, a fan mounted for rotation about a generally vertical axis, the axis of said fan aligned with the center of the aperture in said bottom and with the central axis of the pot, said fan having vanes extending upwardly from the plane of said housing bottom and located radially substantially within the periphery of said pot, and means located between the pot bottom and the bottom of the housing and in the space defined therebetween for causing a radial delivery of the air delivered by said vanes, including a plurality of fixed vanes mounted on and upwardly extending from the bottom of the housing, and located in the direct line of delivery of air from the fan vanes, and terminating at their outer edges adjacent the periphery of the pot, said fixed vanes including generally radial inner portions and being curved laterally toward their outer delivery edges, whereby a substantially circumferential movement is imparted to the air delivered thereby.

3. In a heater, a burner pot having air apertures located at a plurality of levels in its side wall, means for delivering a liquid fuel to the interior of the pot, a substantially air tight housing surrounding and closely adjacent said pot and extending upwardly about said pot, said housing having a bottom portion, said bottom portion having a generally circular aperture in line with the central axis of the pot, the bottom portion being spaced slightly below the bottom of the pot, and means for delivering air under pressure to the space between the housing and the pot, including a motor and fan assembly removable as a unit from the heater, the fan being coaxial with the central axis of the pot, said fan extending through said aperture in the bottom of the housing and having a plurality of vanes located in the space between the bottom of the pot and the bottom of the housing, and of a radius less than the radius of said aperture, and means for securing said motor and fan readily removably upon the bottom of said housing, including opposed interpenetrating elements actuatable from below the bottom of the housing, whereby the motor and fan may readily be applied to or removed from the bottom of the housing, without the necessity of access to the interior of the housing.

4. In a heater, a burner pot having a cylindrical side wall and having air apertures located at a plurality of levels in said side wall, means for delivering a liquid fuel to the interior of the

pot, a substantially air tight housing surrounding and closely adjacent said pot and extending upwardly about said pot, said housing having a bottom portion, said bottom portion having a generally circular aperture in line with the central axis of the pot, the bottom portion being spaced slightly below the bottom of the pot, and means for delivering air under pressure to the space between the housing and the pot including a fan and means for rotating it, the fan being generally co-axial with the pot and having fan vanes located in the space between the bottom of the pot and the bottom of the housing, the fan being of the centrifugal type and being adapted to deliver air outwardly across the bottom of the pot and toward the periphery of said pot bottom and fixed vanes, located in the space between the bottom of the pot and the housing, for controlling the movement of the air said vanes mounted on the inner face of the bottom portion of said surrounding housing and out of contact with said pot.

5. In a heater, a burner pot having an open end, a closed end, and a generally cylindrical side wall, said side wall having air inlet apertures located at a plurality of distances from the ends of the pot, means for delivering a liquid fuel to the interior of the pot, a substantially air tight housing surrounding and closely adjacent said pot, said housing having an end portion, said end portion having a generally circular aperture in line with the central axis of the pot, said end portion being spaced slightly away from the closed end of the pot, and means for delivering air under pressure to the space between the housing and the pot, including a fan and means for rotating it, the fan being generally co-axial with the pot and having fan vanes located in the space between the end of the pot and the end portion of the housing, the fan being of the centrifugal type and being adapted to deliver air generally radially outwardly across the end of the pot and toward the periphery of the end of the pot, and fixed vanes located in the space between the end of the pot and the end of the housing, for controlling the movement of the air, said vanes being mounted on the inner face of the end of said housing and out of contact with said pot.

6. In a heater, a burner pot having an open end, a closed end, and a generally cylindrical side wall, said side wall having air inlet aper-

tures located at a plurality of distances from the ends of the pot, means for delivering a liquid fuel to the interior of the pot, a substantially air tight housing surrounding and closely adjacent said pot, said housing having an end portion, said end portion having a generally circular aperture in line with the central axis of the pot, said end portion being spaced slightly away from the closed end of the pot, and means for 5 delivering air under pressure to the space between the housing and the pot, including a fan and means for rotating it, the fan being generally co-axial with the pot and having fan vanes located in the space between the end of the pot and the end portion of the housing, the fan being of the centrifugal type and being adapted to deliver air generally radially outwardly across the end of the pot and toward the periphery of the 10 end of the pot, and means located in the space between the end of the pot and the end of the housing, for controlling the movement of the air as it flows outwardly from the fan.

7. In a heater, a burner pot having an open end, a closed end, and a generally cylindrical side wall, said side wall having air inlet apertures located at a plurality of distances from the ends of the pot, means for delivering a liquid fuel to the interior of the pot, a substantially air tight housing surrounding and closely adjacent said pot, said housing having an end portion, said end portion having a generally circular aperture in line with the central axis of the pot, said end portion being spaced slightly away from the closed end of the pot, and means for 15 delivering air under pressure to the space between the housing and the pot, including a fan and means for rotating it, the fan being generally co-axial with the pot and having fan vanes located in the space between the end of the pot and the end portion of the housing, the fan being of the centrifugal type and being adapted to deliver air generally radially outwardly across the end of the pot and toward the periphery of the 20 end of the pot, and means located in the space between the end of the pot and the end of the housing, for controlling the movement of the air as it flows outwardly from the fan.

7. In a heater, a burner pot having an open end, a closed end, and a generally cylindrical side wall, said side wall having air inlet apertures located at a plurality of distances from the ends of the pot, means for delivering a liquid fuel to the interior of the pot, a substantially air tight housing surrounding and closely adjacent said pot, said housing having an end portion, said end portion having a generally circular aperture in line with the central axis of the pot, said end portion being spaced slightly away from the closed end of the pot, and means for 25 delivering air under pressure to the space between the housing and the pot, including a fan and means for rotating it, the fan being generally co-axial with the pot and having fan vanes located in the space between the end of the pot and the end portion of the housing, the fan being of the centrifugal type and being adapted to deliver air generally radially outwardly across the end of the pot and toward the periphery of the 30 end of the pot, and means located in the space between the end of the pot and the end of the housing, for controlling the movement of the air as it flows outwardly from the fan.

7. In a heater, a burner pot having an open end, a closed end, and a generally cylindrical side wall, said side wall having air inlet apertures located at a plurality of distances from the ends of the pot, means for delivering a liquid fuel to the interior of the pot, a substantially air tight housing surrounding and closely adjacent said pot, said housing having an end portion, said end portion having a generally circular aperture in line with the central axis of the pot, said end portion being spaced slightly away from the closed end of the pot, and means for 35 delivering air under pressure to the space between the housing and the pot, including a fan and means for rotating it, the fan being generally co-axial with the pot and having fan vanes located in the space between the end of the pot and the end portion of the housing, the fan being of the centrifugal type and being adapted to deliver air generally radially outwardly across the end of the pot and toward the periphery of the 40 end of the pot, and means located in the space between the end of the pot and the end of the housing, for controlling the movement of the air as it flows outwardly from the fan, said means including vanes fixed in relation to said pot and housing.
